REFLECTIVE SAFETY VEST

Louis Spitz, Los Angeles, Calif.
(463 S. Almont Drive, Beverly Hills, Calif. 90212)

Filed Apr. 29, 1974, Ser. No. 465,261

Term of patent 14 years

Int. Cl. D2—02

U.S. Cl. D2—27

Fig. 1

Fig. 2

Fig. 3

Fig. 4

Fig. 5

Fig. 6

Fig. 7

FIG. 1 is a front perspective view of a reflective safety vest showing my new design;

FIG. 2 is a front elevational view thereof;

FIG. 3 is a side elevational view;

FIG. 4 is an elevational view of the other side;

FIG. 5 is a back elevational view;

FIG. 6 is a top plan view; and

FIG. 7 is an enlarged fragmentary view.

I claim:

The ornamental design for a reflective safety vest, as shown and described.
